(57) **CLAIM**

The ornamental design for a standing electric guitar as shown and described.

DESCRIPTION

FIG. 1 is a front view of a standing electric guitar showing my new design;

FIG. 2 is a back view thereof;

FIG. 3 is a left side view thereof;

FIG. 4 is an enlarged top view thereof; and,

FIG. 5 is an enlarged bottom view thereof.

Throughout the views, the broken lines represent the portions of the guitar that form no part of the claimed design. The right side view is not shown as it is a mirror image of the left side view.
